UNITED STATES PATENT OFFICE.

FRANK JEZ AND THOMAS DUFFY, OF TAYLOR, TEXAS.

TAG-HOLDER.

Application filed October 21, 1921. Serial No. 508,302.

To all whom it may concern:

Be it known that we, FRANK JEZ and THOMAS DUFFY, citizens of the United States, residing at Taylor, in the county of Williamson and State of Texas, have invented new and useful Improvements in Tag Holders, of which the following is a specification.

This invention relates to tag holders, and particularly to holders for tags to be exhibited in stores and other merchandising establishments to indicate to prospective purchasers the prices of goods or articles adjacent to which they are exposed.

15 The primary object of the invention is to provide a holder of simplified and improved construction and to which the tags may be quickly applied or removed, and wherein that side of the tag having the indicating 20 means thereon is at all times properly exposed to the view of purchasers.

A further object of the invention is to provide means of an improved nature for applying the tag to a base, such as a table 25 edge, shelf edge or counter, wherein the tag is firmly held properly positioned upon the support or base, and wherein, when desired, the holder in its entirety may be quickly and easily removed from the support.

30 A still further object of the invention is to provide a tag holder having means of an improved nature whereby the same may be applied equally as well to a vertical support as to a horizontal support, and wherein, regardless of the inclination of such securing base, the tag will be in proper position for exhibition.

With these and other objects in view, the 40 invention consists of the features of construction, combination and arrangement of parts, hereinafter fully described and claimed, reference being had to the accompanying drawing, in which:—

45 Figure 1 is a front elevation of store display shelving, and illustrating the application of tag holders constructed in accordance with the invention,

Figure 2 is an enlarged fragmentary sectional view through a horizontal shelf or table top and illustrating the manner in which the tag holder is applied thereto,

50 Figure 3 is a similar view of a vertically disposed support and illustrating the application thereto of the tag holder embodying the invention, and

Figure 4 is a perspective view of the tag holder per se.

Referring now more particularly to the drawing, a case or shelving such as commonly used in stores for the display of goods, is indicated generally at 5, and in the present instance includes at least one horizontally disposed shelf 6, a vertically disposed apron 7 being disposed at the top 60 of the case. The goods to be exhibited will rest upon the several shelves of the case, or upon suitable tables in the store or display room.

The tag holder includes a plate 8 of suitable metal and being of any suitable size, the said plate having its larger portion of substantially rectangular form, and having a reduced ear or finger piece 9 extending from one side of said enlarged portion. The edge 70 of the plate opposite to the finger 9 is bent inwardly in spaced parallel relation to the plate 8, and constitutes a bottom or abutment 10 upon which a card lying upon plate 8 rests. The lateral edges of the plate are 80 similarly turned inwardly and constitute guides 11 adapted to engage around or enclose the edges of the card resting upon the portion 10. The card is indicated generally at 12 and has on the forward face there- 85 of suitable inscriptions (not shown). It is obvious from this construction that the card 12 may be easily applied to or removed from the holder plate, and that when once inserted therein and the edges thereof engaged by the members 10 and 11, the card will be held against accidental disengagement, and that the card will be held in proper position for display or exhibition.

The anchoring or supporting device for 95 the tag holder is indicated generally at 13, and comprises a single strand of relatively stiff heavy wire bent so as to provide a body portion 14 and spaced parallel legs 15 and 16 respectively disposed in the same general direction. The wire is bent at the junction of the body portion 14 with the leg 16 thereof so as to provide a loop or eye portion 17 from which the tag holder or body 8 depends. The legs 15 and 16 are of sub- 100 substantially the same length, and their ends are turned at right angles to the leg portions and in directions opposite to each other and constitute feet 18.

In applying the anchoring member to the 110 tag holder, the arm 16 is passed through opening 19 near the outer edge of the por-

tion 9 of the plate, and the plate is continued in its movement upon said leg until it rests within the loop portion 17. The anchoring member 13 is then fastened to the shelf, table top or apron by passing the legs 15 and 16 over the opposing edges thereof, the resiliency of the wire of which the anchoring member is formed providing sufficient gripping action to tightly maintain the anchoring device upon the support. The extremities of arms 15 and 16 extend in opposite directions and therefore maintain the anchoring device in proper position upon the support and prevent wobbling of the same in either direction. In instances where the support is disposed horizontally, the leg 15 is positioned upon the upper surface of the support while leg 16 engages with the lower surface of the same, the body portion 14 thereof being disposed vertically upon the edge of the table or shelf and the loop 17 is disposed slightly below the lower edge of the table. The tag holder 8 depends from said loop and maintains the tag carried thereby in proper position for exhibition. When it is desired to attach the anchoring device to a vertically disposed apron or support, the leg 16 engages with the rear face of the support while the leg 15 is passed to the front face of the support. The loop 17 of the anchoring device is therefore disposed adjacent to the rear edge of the apron or support and the card 12 is properly presented to the gaze of purchasers. Should it be desired, the tag holder may be removed from the anchoring device and reversed.

From the foregoing it is apparent that a tag so constructed may be quickly and easily applied to a suitable base wherever located with the assurance that the tag carried

thereby will be properly exhibited and will be held firmly against accidental detachment. The holder per se is of such construction that the tag, while held firmly therein, may be quickly and easily replaced ⁴⁵ when occasion demands.

While the above is a description of the invention in its preferred embodiment, it will be understood that various changes in the construction and arrangement of parts ⁵⁰ may be resorted to without departing from the spirit of the invention as defined by the claim.

Having thus fully described our invention, ⁵⁵ we claim:

In a holder for display tag plates, an anchoring member formed of a single strand of spring wire, said wire being bent to provide a body portion straight from end to end thereof, legs projecting in the same direction at right angles to and from the said ends of said body portion and arranged to lie in superimposed relation and in the same plane, feet extending at right angles to and from the extremities of said legs in parallel ⁶⁰ relation to each other equi-distantly in opposite directions beyond the plane of the body portion, and an elongated loop formed in said strand at the juncture of said body and one of said legs and projecting outwardly beyond the opposite side of the body from said leg, said loop having its entrance between the juxtaposed ends of said body and leg and having its major axis lying on a diagonal line passing through the space ⁶⁵ ⁷⁰ ⁷⁵ between the legs.

In testimony whereof we affix our signatures.

FRANK JEZ.
THOMAS DUFFY.
